UNITED STATES PATENT OFFICE.

HORACE T. ADAMS AND HUGO ALTMAYER, OF SAN FRANCISCO, CALIFORNIA.

SPLIT PULLEY.

1,351,197.

Specification of Letters Patent. Patented Aug. 31, 1920.

Application filed September 2, 1919. Serial No. 321,248.

To all whom it may concern:

Be it known that we, HORACE T. ADAMS and HUGO ALTMAYER, citizens of the United States, residing in the city and county of San Francisco and State of California, have invented a certain new and useful Improvement in Split Pulleys, of which the following is a specification.

Our invention relates to improvements in split pulleys wherein a rim segment operates in conjunction with a rim opening to provide a continuous circular periphery; and the objects of our invention are:

First, to provide an improved split pulley;

Second, to provide an improved split pulley having improved means for removing a segment of said rim to facilitate application of the pulley to a line shaft or the like and intermediate the ends thereof or between other apparatus on said shaft where space is limited;

Third, to provide improved means for machining the several parts effectively and economically to aline the several parts concentrically;

Fourth, to provide an improved split pulley of the character described which may be detachably mounted upon hubs of different bore diameters;

Fifth, to provide an improved split pulley of the character described having an improved detachable split hub whereby said hub may be first secured to a line shaft or the like before mounting the pulley rim; and

Sixth, to provide a split pulley of the character described having an improved hub detachably connected thereto whereby rims of various diameters may be applied to said hub without removing said hub from the line shaft, said hub having means for alining said pulley rim concentrically with the shaft and hub thereon.

We accomplish the above and other objects by means of the improved device disclosed in the drawings forming a part of the present specification wherein like characters of reference are used to designate similar parts throughout the said specification and drawings, and in which—

Figure 1 is a broken elevation of our improved device;

Fig. 2 is a broken side view, partly in section; and

Fig. 3 is a side elevation of the split pulley with the rim segment removed disclosing the split hub.

Referring to the drawings the numeral 1 is used to designate a rim having an opening in one side thereof and seats 2 arranged at the transverse edges of said opening. Adjacent the seats 2 we have provided lugs 3 apertured to receive threaded studs 4 which engage threaded apertures 6 within the edges of a rim segment 7 within the opening of the rim 1.

The rim 1 is provided with an internal flange 8 in turn provided with an annular seat 9 to engage the concentric periphery of the flange 11 upon a split hub 12, said rim flange 8 being secured to the hub flange 11.

The rim flange 8 is also provided with an opening aligned with the opening in the rim 1, the said sides of said flange opening being provided with grooves 14 having pockets or recesses 16 therein and arranged parallel to a diameter passing through the flange and rim openings.

The rim segment 7 is provided with an extension 17 whose sides are arranged substantially parallel with and spaced apart from the grooves 14, the purpose of which will hereinafter be more fully set forth.

The split hub 12 is first cast integral and with a longitudinally disposed slot 19 therein said slot 19 extending nearly the entire length of the hub 12 and nearly to the edges of the hub flange 11.

While in this integral condition the hub 12 is bored the required diameter to receive the shaft 20 and the periphery of flange 11 formed concentric therewith, after which said hub is cracked or split apart by inserting a chisel or other suitable tool within the slot 19 and striking said tool with a hammer or the like.

This operation will provide two halves having semicircular seats and lugs at the corners of the hub and flange which lugs are later machined to clear when the two halves of the hub 12 are assembled on the shaft 20. As the hub 12 is bored to fit the shaft 20 before being split it is obvious that the two split halves, when assembled upon said shaft 20, will center the periphery of the hub flange 11 upon said shaft 12.

Bolts 21, or any other suitable device, may be used to securely clamp the split hub 12 upon the shaft 20.

After the split hub 12 has been assembled the rim 1 is fastened to the flange 11 by means of the bolts 15. The rim segment 7 is then seated and firmly secured in position 5 with the extension 17 spaced apart from the grooves 14. After the segment 7 is thus alined with the rim 1 a suitable plastic bearing metal 18 is poured in a molten state into the grooves 14 and pockets 16 thereof so that 10 after said plastic metal has hardened the rim segment 7 may be withdrawn and readily alined when replaced by the plastic metal which correctly positioned and alined said segment relatively to the rim 1 and flange 15 11 when poured.

In operation the rim segment 7 and extension 17 thereof are first removed from the rim 1 of the pulley and the flanged split hub 12 is also disassembled. The two 20 halves of the split hub 12 are assembled on the shaft 20 by means of the bolts and nuts 21, or other suitable securing means, and the rim 1 is then mounted upon the shaft by moving said rim 1 to pass the shaft 12 through the opening in said rim 1 and flange 8 thereof and to engage the annular seat 9 of said rim flange 8 with the periphery of the centered hub flange 11.

The rim segment 7 is next moved into 30 alinement by sliding the extension 17 between the grooves 14 until the edges of said rim segment 7 are properly seated upon the seats 2 adjacent the edges of the opening in the rim 1.

35 The threaded studs 4 are then passed through the apertured lugs 3 to engage the threaded apertures 6 within the edges of the rim segment 7 thereby firmly securing said rim segment 7 in alinement with the 40 periphery of the rim 1.

The extension 17 is then secured to the hub flange 11 by means of the bolts 15.

It is obvious from the foregoing that we have provided a new and improved split 45 pulley detachably mounted upon the split hub whereby the operation of applying said pulley to a line shaft or the like where space is limited, may be facilitated.

It is also obvious that we have provided 50 improved means whereby said pulley rim may be properly alined and centered upon the shaft as well as improved means for alining and centering the split hub.

The details of construction are so sus- 55 ceptible to variation that we do not wish to confine ourselves to the precise construction disclosed in the drawings but rather to avail ourselves of any modification that may fall properly within the scope of the 60 appended claims.

Having thus described our invention what we claim as new and desire to secure by Letters Patent is:

1. A split pulley comprising a hub hav- 65 ing an annular flange; a rim detachably

mounted upon the flange and having an opening in one side thereof; and a rim segment arranged to seat within the opening in the rim and to be detachably connected to the hub flange.

2. A split pulley comprising a hub having an annular flange; a rim detachably mounted upon the hub flange and having an opening in one side thereof and grooves alined with the edges of said opening and parallel with a diameter of the rim passing through the center of said opening, and likewise provided with seats on the edges of said opening; and a rim segment seated upon said seats and detachably connected to the hub flange, said rim segment being also provided with an extension to slidably engage the grooves and hub flange; and means for securing said extension of the rim segment to said hub flange.

3. A split pulley comprising a rim having an opening in one side thereof and a flange having grooves therein arranged parallel with a diameter passing through the center of said opening, said grooves being provided with pockets; a rim segment mounted within the rim opening and having an extension whose sides are arranged parallel with and spaced apart from the grooves; and a plastic filler to fill in the space between the extension edges and the grooves and likewise within the groove pockets to aline the rim segment with the rim.

4. A split pulley comprising a rim having an opening in one side thereof and seats arranged at the edges of said opening; a flange on the rim provided with an opening alined with the rim opening and provided with grooves arranged parallel to a diameter passing through the center of the flange and rim openings, said grooves being likewise provided with pockets; and a rim segment seated within the seats and having an extension provided with edges arranged parallel with and spaced apart from the grooves; and a filler within the grooves and groove pockets and extension to the edges of the extension to aline said rim segment with the rim.

5. A split pulley comprising a rim having an opening in one side thereof and seats arranged at the edges of said opening; a flange on the rim provided with an opening alined with the rim opening and provided with grooves arranged parallel to a diameter passing through the center of the flange and rim openings, said grooves being likewise provided with pockets; a rim segment seated within the seats and having an extension provided with edges arranged parallel with and spaced apart from the grooves; a filler within the grooves and groove pockets and extending to the edges of the extension to aline said rim segment

with the rim; and means for securing the rim segment to the seats on the edges of the rim opening.

6. A split pulley comprising a rim having an opening in one side thereof and seats arranged at the edges of said opening; a flange on the rim provided with an opening aligned with the rim opening and provided with grooves arranged parallel to a diameter passing through the center of the flange and rim openings, said grooves being likewise provided with pockets; a rim segment seated within the seats and having an extension provided with edges arranged parallel with and spaced apart from the grooves; a filler within the grooves and groove pockets and extending to the edges of the extension to aline said rim segment with the rim; means for securing the rim segment to the seats on the edges of the rim opening; a

split hub having an annular flange thereon; and means for securing the rim flange and rim segment extension to the hub flange.

7. The combination with a split pulley having an opening in the side thereof, and a rim segment detachably mounted within said opening of a hub split longitudinally; and means for securing said hub to the detachable rim and rim segment.

8. The combination with a split pulley having an opening in one side thereof and a rim segment detachably mounted within said opening, of a flanged hub split longitudinally; means for centering the rim upon the flange of the hub; and means for detachably connecting said rim to said flange.

In witness whereof we hereunto set our signatures.

HORACE T. ADAMS.
HUGO ALTMAYER.
